(57) **CLAIM**

The ornamental design of a bicycle wheel hub, as shown and described.

DESCRIPTION

FIG. 1 is an isometric view of a bicycle wheel hub incorporating our new design, wherein the portions in phantom form no part of the claimed design;

FIG. 2 is a front elevation view thereof;

FIG. 3 is a rear elevation view thereof;

FIG. 4 is a top plan view thereof;

FIG. 5 is a right end elevation view thereof;

FIG. 6 is a left end elevation view thereof; and,

FIG. 7 is a bottom plan view thereof.
